14 Sheets-Sheet 5

This technical drawing illustrates a complex mechanical assembly, likely a cylinder or actuator, featuring a series of stacked components. The assembly is oriented vertically and includes several cylindrical parts with internal structures and external features. A central vertical line, possibly a central axis or a reference line, is marked with the number 208. Other prominent numbers visible in the drawing include 210, 202, 204, 206, 208, 231, 200, 231, 200, 202, 204, 206, 208, 242, and 231. The drawing uses fine lines and cross-hatching to detail the internal parts and their relative positions. The overall complexity suggests a high-precision industrial component.

MULTICOLOR PROOF PRESS

David D. Vandercoek, Evanston, Edward O. Vandercoek, Kenilworth, and Raymond L. Pelland, Chicago, Ill., assignors, by mesne assignments, to Vandercoek & Sons, Inc., Chicago, Ill., a corporation of Delaware

Application March 22, 1947, Serial No. 736,496

14 Claims. (Cl. 101—208)

1

This invention relates to a printing press, and particularly to a multi-color proof press by which the color composition characteristics of a set of color printing forms may be determined in advance of their application to high speed production presses but under equivalent conditions of operation as exists in such high speed production presses.

The proper preparation of a set of forms for multi-color printing is one of the most expensive and time-consuming steps of the entire process of producing multi-color printed illustrations. It has been found to be entirely insufficient to secure merely a contact impression from the various forms of a multi-color set in advance of the application of such forms to the high speed production presses, inasmuch as the color composition of an illustration produced by a given set of multi-color forms on a high speed production press will vary substantially and unpredictably from that obtained by superposed contact impressions from the same set of forms. It has therefore been recognized that representative proofs can be obtained in multi-color printing only by taking impressions from the set of multi-color forms under conditions which are substantially equivalent to the printing conditions under which such forms will be used in the high speed production press. Heretofore there has not been available any satisfactory proof press which would permit multi-color proofs to be obtained from a set of forms under conditions which were truly representative of those encountered in the production presses and which would therefore provide an accurate proof both as to the configuration of the particular illustration and the multi-color composition.

Accordingly, it is an object of this invention to provide an improved printing press, and particularly an improved proof press for obtaining multi-color proofs from a set of multi-color forms.

Another object of this invention is to provide an improved multi-color proof press wherein the speed of operation and the conditions under which the proof is obtained from the set of multi-color forms are substantially equivalent to that which exists in the high speed production presses in which such forms are to be utilized, hence permitting a multi-color proof to be obtained which is accurately representative of the color printing characteristics of the particular set of forms.

A further object of this invention is to provide an improved multi-color printing press

2 which will accommodate any desired number of forms of a multi-color set and selectively produce proofs from such forms consisting either of a multiple impression of all such forms on a single sheet, a single impression from any selected one of such forms, or a multiple impression of any desired combination of two or more of such forms.

A particular object of this invention is to provide an improved proof printing press wherein the forms of a multi-color set of printing forms are disposed in spaced relationship along a longitudinal bed and a carriage is reciprocably movable over such bed and carries an impression cylinder to which a proof sheet is attached. The inking of the individual forms and the speed of the impression cylinder with respect to such forms are accomplished in such a manner as to provide printing conditions equivalent to those of production presses, and mechanism is provided at one end of the bed for loading successive proof sheets upon the impression cylinder and at the other end of the bed for unloading the printed proof sheet from the impression cylinder.

25 The specific nature of the invention as well as other objects and advantages thereof will become apparent to those skilled in the art from the following detailed description of the annexed sheets of drawings which, by way of preferred example only, illustrate one specific embodiment of the invention.

On the drawings:

Figure 1 is a side elevational view of a complete machine embodying this invention showing the carriage positioned at the loading end of the bed.

Figure 2 is a view similar to Fig. 1 but showing the carriage positioned at the unloading end of the bed.

Figure 3 is an enlarged scale, side elevational view of the loading end portion of the machine of Fig. 1 with the side plates removed.

Figure 4 is an enlarged scale, top elevational view of the central portion of the machine of Fig. 1 showing the carriage traversing such central portion.

Figure 19 is a partial side elevational view of the forward end of the bed, showing the buffer mechanism.

Figure 20 is a partial top elevational view of the bed, showing the frisket chain positioning racks.

As shown on the drawings:

A very general description of a multi-color proof press embodying this invention will be first presented in order that the following detailed description will be rendered more clear with respect to the functions of each of the detail mechanisms in the machine as a whole.

In general, a machine embodying this invention comprises a longitudinal, horizontal bed 10 which is suitably supported on a plurality of spaced uprights 12. At one end of the bed, hereinafter referred to as the loading end and represented as the left hand end of the machine in Figs. 1 and 2, a control box 14 and control panel 15 are provided and feeding platform 16 overlies panel 15 and box 14 and accommodates a stack of sheets to be printed (not shown).

On the top surface of bed 10 there are suitably mounted a plurality of form mounting blocks 20 (Fig. 4) permitting the securing of any desired number of forms 25 of a multi-color set in longitudinally spaced relationship along the bed 10. Beneath the bed 10 a pair of driving motors 26 (Fig. 3) are mounted and in addition, the gear box casing 30 and brakes 40 for each driving motor.

A carriage 100 is mounted on bed 10 for reciprocable movements therealong. Carriage 100 journals an impression cylinder 120 as well as a plurality of sets of inking roller units 150, there being an inking roller unit 150 correspond-

ing to each of the form mounting mechanisms on the bed 10.

As the carriage 100 moves along the bed forwardly, i. e., from left to right as viewed in Figs. 1 and 2, the impression cylinder 120 picks up a sheet of paper (not shown) from the loading platform 16 and such sheet is wrapped around the periphery of impression cylinder 120. The inking roller units 150 selectively engage the forms 25 to apply the desired color of ink to such forms in advance of the impression cylinder. The impression cylinder 120 is vertically moved in the carriage 100 as the carriage moves along the bed so as to selectively engage one or more of the forms 25 and thus produce either single color or multi-color impressions on the sheet of paper carried thereon.

At the extreme forward end of the bed 10, the carriage 100 comes to rest overlying a plurality of ink applicator roll units 200 (Figs. 1 and 6) which selectively engage the inking roller units 150 to apply a predetermined quantity of proper colored ink to each of such units. The printed sheet is released from the impression cylinder 120 at this point, hence the term "unloading" end of the bed.

To prevent the application of any color of ink to any portion of the proof not requiring such color, a plurality of friskets 250 (Figs. 1 and 4) are provided, there being one frisket for each of the forms of the multi-color set. The friskets 250 are supported by a pair of parallel cables 254. The cables 254 are respectively secured at the forward end of the bed to upright support members 256 and at their rearward end are secured to the bed itself. Intermediate portions of the cables 254 are trained over sprockets 264 provided on the top end of uprights 258 on the carriage 100. The cables 254 are also trained over suitable guiding sheaves carried by the carriage 100 so that on the forward movement of the carriage, the friskets are successively laid over their corresponding forms after the inking roller units 150 have passed thereover, but in advance of the impression cylinder 120. On the return movement of the carriage 100, the friskets are picked up from the bed 10 after the impression cylinder 120 has passed thereover but in advance of the inking roller units. Thus the inking roller units 150 may contact their respective forms and apply ink thereto during each direction of movement of the carriage 100. As will be seen, the impression cylinder 120 is permitted to contact selected forms only during the forward stroke of the carriage. Hence only on the forward stroke of the carriage is the proof printing accomplished.

Driving mechanism

Turning now to a detailed description of the various major elements of the printing press embodying this invention, it was heretofore mentioned that a pair of electric motors are suitably mounted underneath the bed 10 and provide all of the driving power for the printing press. While only one of such motors is shown on the drawings, indicated by the numeral 26 (Fig. 3), both motors are respectively connected by suitable belts 27 to input pulleys 28 and 29 which are respectively journaled on opposite sides of a gear box casing 30. While the gear box casing 30 (Fig. 11) is a unitary member, independent sets of speed reducing gears are provided within such gear box which are respectively driven by input pulleys 28 and 29 and the outputs of such gear trains are re-

spectively represented by the shafts 31 and 32. A sprocket 33 is mounted on shaft 31 and this sprocket supplies driving power for the inking roller units through a chain 34 (Fig. 7). Output shaft 32 drives a shaft 35 through gears 36 and a sprocket 37 is mounted on shaft 35 which drives a chain 38 (Fig. 7) to provide power for the reciprocable movement of the carriage 100 on the bed 10.

A pair of brake elements 40 (Fig. 11) are respectively associated with hubs 42 which are co-rotatable with input pulleys 28 and 29. Since the brake mechanisms 40 are functionally substantially identical, only one of such mechanisms will be described in detail. It should be understood that the illustrated form of brake mechanism 40 constitutes merely a preferred form and that any other one of several well known forms of solenoid actuated, braking mechanisms could be advantageously employed.

Each braking mechanism 40 comprises a pair of substantially semi-circular braking arms 41 which have their one ends pivoted together as indicated at 44 and are suitably shaped to snugly surround the brake drums 42. The free ends of 25 brake arms 41 are turned outwardly in parallel relationship and are urged together by a spring 48 which is mounted on a support rod 50. The force exerted by spring 48 is sufficient to cause the brake arms 41 to exert a clamping action on the drum 42 and hence to rapidly brake the movement of the drum 42 and to substantially lock the drum 42 against rotation. To release the braking action an eccentric 50 is provided to which is suitably connected a pair of links 52 which have their other ends respectively connected to the free ends of the brake arms 41. Hence rotation of eccentric 52 will force such free ends apart and release the braking action. Such rotation of the eccentric 52 may be conveniently produced by a solenoid 56. As will be brought out in detail later, the control circuit for each solenoid 56 is interlocked with the control circuit for each of the driving motors so that when either driving motor is energized, its cooperating braking mechanism 40 is released.

As was heretofore mentioned, the sprocket 37 drives the carriage operating chain 38. Sprocket 37 is disposed at the loading end of the bed 10 (Fig. 7) and the chain 38 extends substantially the full length of bed 10, being trained over a sprocket 39 suitably journaled at the forward end of bed 10. Chain 38 is suitably secured to carriage 100 as by a buffer arm 62 which has an end pivotally mounted to a block 60 provided in depending relationship on carriage 100, and the other end of buffer arm 62 pivotally secured to one of the links of chain 38. This latter end of buffer arm 62 is provided with a projecting portion 64. Projection 64 is arranged to engage the movable element 66 of a hydraulic buffer mechanism 68 which is suitably mounted at the rear end of the bed 10. A similar buffer mechanism 69 is provided at the forward end of bed 10 (Fig. 19) and is engaged by a notch 65 on buffer arm 62. Hence when carriage 100 is moved to either end of bed 10, its inertia is absorbed by hydraulic mechanisms 68 or 69 respectively and brake 40 and it is brought rapidly to a stop without exerting undue forces on the bed 10.

As was previously mentioned, the chain 34 driven by sprocket 33 provides driving power for the inking roller units which are carried by the carriage 100. Chain 34 likewise extends the full length of the bed 10 and is trained around suit-

able idler sprockets 10 provided at both the forward and rear ends of the bed 10 and also around drive sprockets 238 of the ink applicator units 200. The loop of chain 34 is disposed in a substantially vertical plane and the top side thereof lies substantially flush with the top of bed 10. In said position the chain 34 is conveniently engaged by a sprocket 72 (Fig. 15) which is journaled on the carriage 100.

From the aforescribed construction, it is apparent that the sprocket 72 on the carriage 100 may be driven by chain 34 in two independent manners. When the carriage 100 is stationary with respect to the bed 10, then the sprocket 72 may be rotated by energization of the driving motor associated with the sprocket 33. During the traversing movement of the carriage 100 along the bed 10, however, if the chain 34 is locked in position with respect to the bed 10, as by the braking action of the brake mechanism 40 associated with the driving mechanism of the sprocket 33, then the sprocket 72 will be rotated by the chain 34 in the same fashion as a gear is rotated by rolling along a fixed rack.

In accordance with this invention, the first condition of rotation of sprocket 72 is permitted to occur only when the carriage 100 is positioned at the forward end of the bed 10, where each of the inking roll units 150 are in engagement with its corresponding ink applicator roll unit 200, or when the carriage 100 is at the rear or loading end of the bed. At any other position of the carriage 100 on the bed 10, the inking roll driving motor, hereinafter referred to as M_r , is deenergized and the brake 40 associated with its driving mechanism is applied.

In Fig. 17 there is shown in schematic form a suitable circuit for accomplishing such selective energization of the carriage driving motor M_c and the inking roll driving motor M_r . In this circuit diagram the braking mechanism 40 associated with each motor is indicated schematically respectively by the numerals 40c and 40r and the actuating solenoids for such braking mechanism by the numerals 56c and 56r. A pair of contactors 76c and 76r are provided to respectively control the energization of the carriage driving motor M_c and its associated braking mechanism 40c and the inking roll unit driving motor M_r and its associated braking mechanism 40r. The coils of contactors 76c and 76r are electrically connected in parallel across a voltage source V respectively through the normally closed contacts 78c and the normally open contacts 78r of a limit switch unit 78. Limit switch unit 78 is suitably arranged with respect to carriage 100 so as to be actuated to close contacts 78c and open contacts 78r when the carriage 100 arrives either at the forward end of the bed 10, in a position wherein the inking roll units 150 are respectively engaged with the ink applicator rolls 200 or at the rear end of the bed 10. The contactor 76r when energized through limit switch unit 78 closes its contacts to simultaneously energize the inking roll unit driving motor M_r and the brake controlling solenoid 56r which releases the braking mechanism 40r associated therewith. A similar function is performed by contactor 76c when energized, but with respect to the carriage driving motor M_c and its associated brake controlling solenoid.

From the foregoing description, it is apparent that the inking roll unit M_r is deenergized and its brake applied thereto at all times during the operation of the carriage driving motor M_c . However, when the carriage 100 arrives at either

end of the bed 10, the carriage driving motor M_C is deenergized and its brake applied and the inking roll unit motor M_I is then energized and its brake released.

It will, of course, be understood by those skilled in the art that supplementary controls are provided for the carriage driving motor M_C which will permit such motor to be energized at the forward end of the bed to move the carriage on its return stroke and to reverse the direction of rotation of such motor when the carriage has returned to the rearward or loading end of the bed. Also, it will be desirable to incorporate controls providing at least two speeds of operation for the carriage driving motor M_C . However, all of such controls may comprise any one of several conventional forms and hence will not be described in further detail herein, except to point out that it is convenient to provide a plurality of foot controls 78 for carriage motor M_C along the length of the bed 10, such for example as adjacent the forward, intermediate and rear end portions of the bed as best shown in Figs. 1 and 2.

Carriage mechanism

The carriage 100 comprises a frame member of generally rectangular configuration having hollow, longitudinal extending side wall portions 101 and 102 and transverse wall portions 103 and 104 (Fig. 4). The longitudinal side wall frame portions 101 and 102 respectively overlie a substantial portion of the side walls of bed 10 and a plurality of support rollers 105 (Figs. 14 and 15) are suitably journaled in the side frame members of carriage 100 to support carriage 100 for free reciprocal movement along bed 10, the rollers 105 engaging longitudinal flanges 106 provided on opposite sides of the bed 10.

On the top horizontal surface of bed 10 there is provided a plurality of form support blocks 20 (Fig. 4) of conventional configuration having a plurality of dovetail grooves 82 therein to receive form clamps 84 to permit a plurality of forms to be positioned in longitudinally spaced relationship along the bed 10 and in identical transverse relationship with respect to the bed 10. Generally, four such form support blocks 20 will be provided, inasmuch as most multi-color printing processes employ forms corresponding respectively to the three primary colors and black. It will, of course, be understood that any desired number of form support blocks 20 may be incorporated in a machine embodying this invention merely by appropriate design of the length of the bed 10.

In the rear end of carriage 100, or the left hand end thereof as viewed in Figs. 1 and 2, an impression cylinder 120 is mounted, disposed in overlying, transverse relationship with respect to the top surface of the bed 10. Impression cylinder 120 is suitably journaled on a coaxial shaft 122 (Figs. 13 and 14). The ends of said shaft are respectively journaled in carriage side walls 101 and 102 in eccentric bearings 124. Hence the vertical position of impression cylinder 120 with respect to the bed 10 may be controlled by rotation of shaft 122 in its eccentric bearings 124.

At the front face of carriage 100 as viewed in Fig. 1, a radial arm 126 is suitably secured to shaft 122 which connects such shaft to a positioning control linkage. The positioning control linkage comprises a link 128 which has its ends pivotally secured respectively to radial arm 126 and to a radial arm 130 which is co-rotatable with a pinion 132. Pinion 132 is in turn driven

by a sector gear 134 which is suitably journaled on the side wall 101 of the carriage frame on a stud shaft 136. The pivotal movement of sector gear 134 is in turn controlled by a cam follower arm 138 which has a cam roller 140 secured thereto and engaged in a longitudinally extending cam track 142 provided along the side of the bed 10.

Cam track 142 in reality comprises a pair of parallel, vertically spaced grooves or recesses 142a and 142b, respectively, which extend the entire length of bed 10. At the rear end of the bed 10, the cam roller 140 is always engaged in the upper groove 142a. An angular surface 144a (Figs. 1, 2 and 3) communicating between grooves 142a and 142b is provided near the rear end of the bed to insure the positioning of cam roller 140 in upper groove 142a at such end. Likewise, an angular surface 144b is provided at the forward end of bed 10 to insure that the cam roller 140 will always be positioned in the lower groove 142b when the carriage 10 is adjacent its extreme forward position on the bed 10.

The vertical spacing of the grooves 142a and 142b is selected to control the vertical movement of impression cylinder 120 with respect to the bed 10 between a printing and a non-printing position. Thus when cam roller 140 is engaged in upper cam groove 142a, the eccentric bearing support for the impression cylinder 120 lowers the impression cylinder sufficiently to engage such cylinder with the forms 125 with proper pressure for a printing operation. When cam roller 140 is engaged in lower cam groove 142b, then the impression cylinder 120 is raised above the bed 10 to a non-printing position.

At spaced intervals along the cam track 142, corresponding to the spacing of the forms 25 on the bed 10, switch mechanisms 146 are provided to permit the cam roller 140 to be selectively switched from one cam groove to the other as the carriage 100 traverses the bed 10 in the forward direction. While any form of switch mechanism might be utilized, I preferably employ a pair of cooperating switch arms 146a and 146b respectively for each of the switch mechanisms 146. The switch arm 146a is the primary switch member and is pivoted to the side wall of bed 10 at its forward end, hence permitting the rear end thereof to be selectively moved about the pivot from a position projecting into the bottom groove 142b to a position projecting into the top groove 142a.

It will be immediately apparent that switch arm 146a is effective to shift the cam roller 140 from one of the cam grooves to the other only during the forward movement of the carriage on the bed 10. On the rearward movement of the carriage, the switch arm 146a is merely deflected out of the path of the cam roller 140. Hence, since the cam roller 140 is always positioned in the bottom cam groove 142b at the beginning of each rearward stroke, it follows that the cam roller 140 always remains in the bottom groove 142b throughout its rearward stroke until it engages the inclined surface 144a near the rear end of the bed 10 whereupon the cam roller 140 is transferred to upper groove 142a. Hence, the impression cylinder 120 is maintained in a non-printing position with respect to the bed 10 throughout its rearward stroke and starts each forward stroke in a printing position with respect to the bed 10.

The secondary switch arm 146b is pivoted at its rear end to the side walls of the bed 10 and

functions only as a guard rail with respect to the cam roller 140 during the switching movement of such roller. Each arm 146b is pivotally biased by a suitable spring (not shown) to a normal position wherein it projects into upper cam groove 142a. Hence switch arm 146b can obviously never have any effect upon the cam roller 140 during the rearward movement of the carriage 100 along the bed 10.

It should be noted that the front and rear-most switch unit 146 is disposed immediately adjacent to the inclined surfaces 144a and 144b, respectively. With such arrangement, it is only necessary to provide a primary switch arm 146a adjacent inclined surface 144a and a secondary switch arm 146b adjacent inclined surface 144b.

The pivotal position of each of the primary switch arms 146a is controlled by an individual cable 148, all of which extend rearwardly along the bed 10, trained over suitable guide pulleys, 20 and are secured to manually operable reels 151. To resiliently bias switch arm 146a to one of its extreme pivotal positions, a spring 149 (Fig. 3) is provided which cooperates between each cable 148 and the bed 10. Hence manual turning of the reels 151 in opposite directions will respectively move the switch arm 146a from one to the other of its extreme pivotal positions. In addition a master lever 145 is provided which will simultaneously move all of the cables 148 to move all the switch arms 146a from one position to another.

It is therefore apparent that the vertical position of the impression cylinder may be selectively controlled between a printing and non-printing position with respect to any one of the forms 25 by manipulation of the particular switch arm 146a which lies in advance of that portion of the cam track 142 corresponding to the location of the selected form. Hence, assuming that four forms are mounted on the bed 10, in the traverse of impression cylinder 120 across the bed, the impression cylinder may be selectively engaged with all four forms in succession, or any one of the forms alone, or any combination of less than the entire number of forms. Hence utmost versatility in obtaining either multi-color proofs or individual color proofs is provided.

The impression cylinder 120 rotates only while the carriage 100 is traversing the bed 10. Such rotation of impression cylinder 120 is produced by a gear 121 (Figs. 13 and 14) which is coaxially secured to impression cylinder 120. Gear 121 engages a rack 123 which extends along the entire length of the top surface of bed 10. Therefore the longitudinal position of any point on the surface of impression cylinder 120 with respect to any one of the forms 25 is definitely determined by the rack 123. To increase the accuracy of the locating action of rack 123, those portions of the rack which correspond to the position of the cylinder when engaging the forms 25 are machined to a high degree of accuracy and provide a close fit with the teeth on the cooperating cylinder gear 121. Intermediate portions of the rack 123 are machined to provide greater clearance between the teeth of the rack and the cooperating gear and hence diminish the friction therebetween and the effort required to drive the carriage 100 along the bed 10. This may be conveniently accomplished by lowering the pitch line of the teeth of such sections. This condition is best illustrated in the exaggerated showing of Fig. 18, wherein the portions 123a represent the fine fit, highly accurate locating

portions of the rack 123 while the portions 123b represent the coarse fit intermediate portions of the rack.

While not shown in detail, it will be understood that the impression cylinder 120 is provided with a conventional paper grasping mechanism so that the loading of successive paper sheets on the cylinder will be accomplished automatically each time that the cylinder moves to the rear end of the bed adjacent the loading platform 16. Such mechanism may for example comprise a pair of relatively movable jaws (not shown) extending along the length of the cylinder which are opened by a suitable cam mechanism 107 when the cylinder 120 arrives at the rear end of the bed 10. Since such mechanism forms no part of this invention, it will be unnecessary to describe such in further detail except for the pointing out that in Figs. 15 and 16 there is shown the cam operated linkage 107 which is mounted on the carriage 100 to actuate the paper holding mechanism of the impression cylinder 120. Linkage 107 comprises a vertical shaft 107a suitably journaled in the side wall of carriage 100 and having a cam follower arm 107b and roller 107c secured thereto at the lower end and an actuating arm 107d and roller 107f secured to its other end. Hence an outward movement of cam follower arm 107b with respect to the bed 10 produced by a suitable cam (not shown) will produce an inward movement of cam actuating arm 107d which may be utilized to release the paper clamping mechanism (not shown). Hence paper sheets may be successively loaded on impression cylinder 120 each time that the carriage 10 arrives at its rearward position and unloaded therefrom each time that the carriage 10 arrives at its forward position. As was heretofore pointed out, all printing contact of the impression cylinder 120 with any selected forms 25 occurs during the forward stroke of the carriage with respect to the bed 10.

Inking roller units

As was previously mentioned, the inking roller units 150 are mounted in the carriage 100. There is an inking roller unit 150 corresponding to each of the form support blocks 20. Hence in the particular machine herein described, four inking roller units 150 are provided.

The inking roller units 150 are mounted in longitudinally spaced relationship on the carriage 100, forwardly of impression cylinder 120. Since each of the four units is identical, only one will be described in detail.

As best shown in Figs. 8 and 9, each inking roller unit comprises an assemblage of two inking rolls or form rollers 152 which apply ink to one of the forms 25 on the bed 10 and a distributing roller 154 which is mounted in frictional engagement with both of the form rollers. The form rollers 152 are each journaled in opposed open slot bearing members 156. The bearing members 156 are respectively mounted on the top of posts 158 which are vertically slidable in the frame side walls 101 and 102 of the carriage 100. On one pair of opposed bearing members 156, upstanding support members 160 are provided which in turn support brackets 162 having upwardly open slots 164 formed therein. The shaft 166 of distributing roller 154 is journaled at each end in a bearing member 168 having a generally rectangular exterior configuration. Bearing members 168 are adjustably mounted on bearing support arms 170, respectively, and the bear-

ing support arms 170 are in turn pivotally mounted at one end thereof on a transverse rod 172 which is vertically supported in the slots 164. Hence the distributing roller is gravitationally biased downwardly into concurrent engagement with the two form rollers 152 of each inking roll unit 150. To prevent inadvertent disassembly of the transverse rod 172 from the open top slots 164 a spring pressed retaining detent 174 is provided in the side walls of the slots 164.

The vertical position of the form rollers 152 with respect to the bed 10 is controlled as the carriage 120 moves across the bed to engage each set of form rollers 152 only with the form 25 corresponding thereto. As will be seen, each set of form rollers 152 is supplied with a different color of ink and hence it is of utmost importance that the form rollers contact only the color form corresponding to the ink color carried by the particular form roller.

The vertical position of the form rollers 152 is of course determined by the vertical position of the movable posts 158. A portion of each of the posts 158 is cut away and provided with rack teeth 176. A horizontal shaft 178 is journaled in the carriage side walls and supports at each end thereof a sector shaped gear 180 whose teeth are meshed with the adjacent rack teeth 176. In the center of shaft 178 a sector gear 182 is secured which meshes with rack teeth 184 formed on a cam follower 186 which is mounted in the corresponding carriage side walls for lateral movement with respect to said side walls. A roller 188 is mounted on the bifurcated, inner end of cam follower 186 to engage in a suitable cam track 190 formed on the side wall of the bed 10.

From the foregoing description, it will be apparent that the vertical position of the form or inking rollers 152 is determined by the lateral position of the cooperating cam followers 186 with respect to the bed 10. The innermost lateral position of cam followers 186 lowers the vertical position of the form rollers 152 with respect to the bed 10 and hence permits the form rollers to engage their corresponding forms 25. Accordingly, the cam tracks 190 controlling the lateral position of cam follower 186 may conveniently comprise a groove in the side walls of the bed 10. Obviously, a separate cam track 190 is provided for each inking roll unit 150 and accordingly, four grooves are provided along the side wall of bed 10, each groove portion being located adjacent the position of one of the form support blocks 12.

It is therefore assured that each time the carriage 100 moves across the bed 10, each set of form rollers 152 will be respectively engaged with one and only one of the forms 25 mounted on the bed 10.

In the event that a lesser number of forms are employed in the particular printing operation, or if for any reason it is desired that a particular set of form rollers do not contact their corresponding form on the bed 10, such set of form rollers may be permanently maintained out of engagement with their corresponding forms by operation of a manual raising mechanism. Such mechanism comprises a shaft 192 extending transversely across the carriage 100 immediately beneath and between the form rollers 152. At the front end of shaft 192, a manual operating handle 194 is secured. A cam block 196 (Fig. 8) is adjustably secured in rigid depending relationship by a bolt linkage 198 to each bearing support arm 170 for the distribut-

ing roller 154. In the bottom face of cam block 196 a downwardly opening slot 197 is formed and a cam roller 195 is journaled in such slot. A pair of cams 199 are then mounted on and secured to shaft 192 immediately underlying rollers 195. Such cams have a peripheral surface suitably shaped that actuation of handle 194 from one pivotal position to another will raise cam block 196 and distributing roller 154 upwardly and lock the handle in such position by the gravitational bias of the weight supported by the cam blocks. On opposite sides of the cam blocks 196, integral projections 193 are provided which respectively extend beneath integral projections 191 provided on the form roller bearing supports 156. If desired, guide pins 189 may be secured in depending relationship to the bearing support projections 191 and project downwardly into suitable vertical apertures formed in the projections 193 on the cam blocks 196. Therefore, when cam blocks 196 are raised by cams 199 sufficiently to engage projections 193 with bearing support projections 191, the bearings 156, and hence the form rollers 152, will be moved upwardly with respect to the bed 10 and locked in such upward position until manually released by return of handle 194 to its original position.

As was previously mentioned, a sprocket 72 is suitably journaled on the carriage 100 adjacent the back side thereof and is engaged by the inking roller driving chain 34. Sprocket 72 is shaft-coupled to a pinion 183 which in turn drives a gear 187 secured to a belt pulley 179. On the back end of the shaft of each of the form rollers 152 an adjustable pulley 177 is secured. As best shown in Fig. 10, adjustable pulley 177 comprises a well known form wherein one conically faced sheave 177a is axially adjustable with respect to an opposed conically faced sheave 177b to obtain a variation in effective circumference of the pulley when engaged by a V belt. A suitable V belt 175 is trained around the belt driving pulley 179 and then successively over each of the adjustable pulleys 177 secured to each of the form rollers 152. A plurality of idler pulleys 173 are journaled on the carriage in any suitable manner to assist in the training of the V belt over a sufficient extent of the periphery of each of the adjustable pulleys 177.

It is therefore apparent that the described arrangement permits highly accurate adjustments to be made of the peripheral surface speeds of each set of form rollers. As will be appreciated by those skilled in the art, it is extremely desirable that each pair of form rollers of an inking roll unit have substantially identical peripheral surface speeds and that speed should exactly equal the speed of movement of the carriage relative to the forms, so as to eliminate the possibility of one of the rollers exerting a sliding action when in contact with its corresponding form 25. While it is a simple matter to obtain identical rotational speeds of a pair of cooperating form rollers, it has heretofore been very difficult to obtain identical surface speeds of the form rollers and carriage due to the practical impossibility of obtaining form rollers of identical diameters or maintaining such diameters identical once the form rollers are in use, since the material from which the form rollers are made is relatively deformable.

The distributing roller 154 is preferably mounted on its shaft 166 in a well-known manner so as to have an axial reciprocatory move-

ment produced by its rotation. Such reciprocal movement facilitates the even distribution of ink to the surface of the form rollers 152. Such mechanism per se, however, forms no part of this invention and has therefore not been described or illustrated in detail.

Referring back to the description of the driving mechanism for the inking roller chain 34, it will be apparent that the form rollers 152 are continually in rotation irrespective of whether the carriage is moving along the bed or positioned at the forward end of the bed adjacent the ink applicator roll mechanism 200 or at the rear end of the bed. Hence the ink on the form rollers is always maintained in proper condition for distribution to the forms.

Frisket applying mechanism

In multi-color printing there are certain areas on the original plates which must be masked off by means of a frisket when making proofs.

In a machine embodying this invention, a frisket support frame is provided for each one of the form support blocks 12. Such support frames constitute merely spaced parallel members 252 (Fig. 4) which are supported between a pair of parallel flexible frisket support cables 254 and are provided with suitable means (not shown) for supporting a frisket 250 therebetween. Preferably the frisket support cables 254 take the form of flexible chains which greatly facilitates the synchronization of the position of the friskets with respect to their corresponding forms.

At the forward end of the bed 10, the support chains 254 are respectively secured to the top of uprights 256 which are in turn suitably secured to the bed 10. A plurality of uprights 258 are formed on the carriage 100 and sprockets 264 are suitably mounted on the top of uprights 258 and the support chains 254 trained thereon. From the rearmost sprockets 264, the frisket support chains pass downwardly and are trained around suitable grooves 266 provided in the periphery of impression cylinder 120. The rear ends of sprocket support chains 254 are fixedly secured to the rear end of bed 10 in any suitable manner.

From the foregoing description, it will be apparent that as the carriage 100 moves forwardly on bed 10 and impression cylinder 120 rotates on rack 123, the frisket support chains 254 will be progressively trained under the impression cylinder 120 to lie on the top of bed 10. Hence, the friskets 250, which are supported in longitudinally spaced relationship along the support chains 254 at spacings corresponding to the location of their corresponding forms 25 on the bed 10, will be successively overlaid on their proper forms 25. To assure correct longitudinal alignment of the friskets with the forms, a plurality of sets of locating racks 255 (Fig. 20) are provided on the bed 10 to mesh with chains 254 adjacent each of the forms 25.

The operation of the friskets is particularly well illustrated in Fig. 4 wherein the carriage 100 is shown in an intermediate position along the bed 10 wherein the first frisket 250 has been superimposed on a corresponding form 25, the second and third friskets do not show, being in the vertical portion of the travel of the frisket support chains 254 parallel to the rear upright 258, and the fourth frisket 250 is shown in its position vertically superimposed above the carriage 100. Further movement of the carriage 100 toward the right as viewed in Fig. 4 will superimpose the second and third friskets over

their corresponding forms and bring the fourth frisket 250 down over the vertical portion of the travel of the frisket support chains 254 and then superimpose such frisket over the fourth form 25.

It should be particularly noticed that on the forward movement of the carriage 100, the friskets are applied to their corresponding forms subsequent to the engagement of the corresponding inking roller units 250 therewith but in advance of the engagement of the impression cylinder 120. On the return movement of the carriage 100 along the bed 10, the friskets are picked up from their superimposed position with respect to the forms 25 in advance of the passage of the inking roll units over such forms but subsequent to the passage of the impression cylinder 120. However, on the return stroke, it will be remembered that the impression cylinder 120 does not engage any of the forms 25. Hence in either direction of movement of the carriage 100 on the bed 10, the friskets are completely removed from the forms when the inking roll units 150 pass thereover and hence the friskets never interfere with the inking operation.

Ink applicator mechanism

As was previously mentioned, the ink applicator units 200 are mounted within the bed 10 at the extreme forward end thereof. There is a separate ink applicator mechanism corresponding to each of the inking roll units 150, and since such applicator mechanisms are identical, only one unit will be described in detail.

Each ink applicator unit comprises a fountain roll 202, a transfer or doctor roll 204 and an ink applicator roll 206, all of which are mounted in the bed 10 adjacent the top surface thereof and in transverse relationship thereto. Cooperating with the fountain roll 202 is an ink applicator blade 208 which is of conventional construction and is adjustably positioned with respect to the surface of fountain roll 202 by a plurality of fountain adjusting bolts 210. Ink in paste form and of the desired color may be manually applied in the trough defined between blade 208 and the surface of fountain roll 202 and rotation of the fountain roll 202 with respect to blade 208 will apply a layer of ink of selected thickness to the surface of fountain roll 202.

In accordance with this invention, fountain roll 202 is incrementally rotated as a function of the cyclic movement of carriage 100 on bed 10. In such manner, a predetermined quantity of ink is applied to fountain roll 202 and hence eventually to the corresponding inking roll unit 150 for each cycle of reciprocal movement of the carriage 100. Incremental rotation of fountain roll 202 is accomplished through a ratchet 212 (Fig. 6) which is corotatably secured thereto. An elongated bar 214 is slidably mounted in one of the side walls of bed 10 and has a suitable crank connection (not shown) at one end thereof to the carriage driving mechanism to produce a reciprocal longitudinal movement of bar 214 for each cycle of movement of carriage 100 across forward and back across the bed 10. A rack member 216 is secured to bar 214 and cooperates with ratchet 212 to incrementally rotate fountain roll 202 a predetermined distance in one direction for each cycle of movement of carriage 100.

To permit adjustment of the extent of rotation of fountain roll 202 imparted by rack member 216 and hence to control the quantity of ink transferred to the inking roll unit per cycle of movement of carriage 100, the rack member 216

is pivotally mounted at one end to the bar 214 on a pin 215 and is urged by springs 218 to a pivotal position wherein it tends to engage ratchet 212 throughout the entire movement of bar 214 in the ratchet actuating direction. The actual pivotal position of rack unit 216 with respect to bar 214 is controlled by an arm 220 secured to rack unit 216 and having a cam follower roller 222 in engagement with a fixed cam surface 224. Cam surface 224 is formed on a cam member 226 which, though fixed to the bed 10 during operation, may be manually adjusted longitudinally of the bed 10 through any conventional form of screw mechanism (not shown) operated by hand wheel 228. Hence the cam surface 224 will selectively control the extent of engagement of rack unit 216 with ratchet 212 per cycle of movement of the carriage 100 with respect to the bed 10.

The transfer or ductor roll 204 effects the transfer of the controlled quantity of ink applied to the surface of fountain roll 202 to the ink applicator roll 206, which, as will be seen, supplies the ink to the corresponding inking roll unit 150 when the carriage 100 is positioned at the forward end of the bed 10.

Transfer roll 204 is journaled on a pair of arms 230 which are pivotally mounted at an intermediate point along their length of the bed 10. Pivotal movement of the arms 230 will thus selectively engage transfer roll 204 with either fountain roll 202 or applicator roll 206. A spring 231 (Fig. 5) normally urges transfer roll 204 into engagement with applicator roll 206. The selective engagement of transfer roll 204 with fountain roll 202 is controlled by a cam block 232 which is secured to the underside of the reciprocating bar 214. A cam follower roller 234 is suitably mounted on the other end of the transfer roll support arm 230 and cooperates with cam block 232. Cam block 232 is suitably located with respect to roller 234 so that the transfer roll 204 is pivoted into engagement with fountain roll 202 only during a period approximately equivalent to the time required for the maximum incremental rotation of fountain roll 202 which the rack member 216 is capable of producing. At all other times, the transfer roll is maintained in engagement with ink applicator roll 206.

As has been previously mentioned the carriage 100 comes to rest in its extreme forward position overlying the ink applicator roll mechanism 200 at the end of each forward stroke and requires manual operation of one of the carriage motor control switches to return the carriage to the rear end of the bed. In the forward position of the carriage illustrated in Fig. 2, each set of form rollers 152 are respectively positioned in concurrent engagement with the ink applicator rolls 206. To effect such engagement, it is of course necessary that the mechanism controlling the vertical position of the form rollers 152 operate to drop such rollers into engagement with the respective ink applicator rolls. This may be conveniently accomplished by providing grooves 190 in the side walls of the bed which are engaged by the cam follower rollers 188 of the vertical positioning mechanism for the form roller unit. The additional grooves 190a thus constitute in effect an extension of the cam tracks 190.

The drive for the ink applicator rolls 206 is derived from the inking roll drive chain 34. Adjacent the forward end of bed 10 a pair of idler sprockets 236 (Fig. 6) are provided which assist in training the chain 34 over a sprocket 238. Sprocket 238 in turn drives a smaller sprocket 75

240 which drives a chain 242 which is suitably trained over a plurality of sprockets 244 respectively provided on each of the ink applicator rolls 206. Hence the ink applicator rolls 206 are rotated only when the inking roll driving motor is energized, and as has been heretofore pointed out, such energization occurs only when the carriage 100 is positioned at either end of the bed 10.

It is believed that the operation of the entire machine will now be clearly apparent to those skilled in the art in view of the foregoing detailed description of the various cooperating mechanisms. While primarily designed for use as a multi-color printing press, it is of course obvious that the press embodying this invention may be equally adaptable to use in any printing operation requiring multiple impressions to be made upon a single sheet. Hence in the attached claims, the generic term "multi-impression printing press" has been adopted.

A press constructed in accordance with this invention may be readily operated to produce a printing speed on the order of 200 feet per minute. While this speed may not be as high as that achieved in modern high speed production presses, it has nevertheless been found that such speed is sufficient to yield accurately representative color proofs so that color proofs obtained on a proof press embodying this invention will indicate the color composition to be expected from the forms when applied to a production press.

No effort has been made in this specification to describe in detail the various manual control switches and relays by which the energization and speed control of the carriage driving motor of the printing press is controlled, except that the interlocking circuit arrangement of such motor with the inking roll driving motor has been shown in Fig. 17 and heretofore been described in detail. Such control circuits are entirely conventional; as are a plurality of indicating lights 5 which are provided on the machine to indicate various conditions of operation thereof.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. In a printing press having a longitudinal, horizontal bed adapted to support a form and a carriage reciprocably movable along said bed, the improvements of a pair of vertically movable posts supported in opposite sides of said carriage, bearings respectively carried by said posts, an inking roller journaled in said bearings, a pair of identical, longitudinally extending cam tracks respectively provided on opposite sides of said bed, cam followers respectively engaged in said cam tracks, a first gear rack on each of said posts, a second gear rack on each of said cam followers, and compound gears journaled in said carriage connecting said first and second gear racks, each of said compound gears having a first toothed sector engaging said first rack and a second toothed sector engaging said second rack whereby said cam tracks control the vertical position of said inking roller with respect to said bed to engage said form as said carriage moves along the bed.

2. The combination defined in claim 1 where-
75 in said cam tracks respectively comprise long-

tudinally extending grooves in the walls of said bed.

3. A printing press comprising a bed, a carriage reciprocably movable along said bed, first driving means for moving said carriage along said bed, an inking roller journaled on said carriage, an ink applicator roll journaled on said bed and arranged to engage said inking roller when said carriage is adjacent thereto in an inking position, a second driving means including a chain positioned along said bed, a sprocket mounted on said carriage and engaging said chain and having a driving connection with said inking roller, and means controlling the energization of said first and second driving means to deenergize said first driving means and energize said second driving means when said carriage arrives at its inking position on the bed and to deenergize said second driving means when said first driving means is energized, whereby said inking roller is driven by said chain in said inking position and rolls on said chain as a rack when said carriage traverses said bed.

4. The combination defined in claim 3 plus braking means for said second driving means, and means for actuating said braking means concurrently with the deenergization of said second driving means to lock said chain to said bed to function as a rack.

5. In a printing press having a bed, a carriage reciprocably movable on said bed, an inking roller journaled on said carriage and means for applying ink to said inking roller at one position of said carriage, the improvements of a driving chain positioned along said bed, power means for moving said chain, a sprocket journaled on said carriage and engageable with said chain, means connecting said sprocket and said inking roller in driving relation, and means for energizing said power means when said carriage is located at said one position, whereby said inking roller is driven by said chain in said inking position and rolls on said chain as a rack when said carriage traverses said bed.

6. The combination defined in claim 5 plus braking means for said power means, and means for actuating said braking means concurrently with the deenergization of said power means to lock said chain to said bed to function as a rack.

7. In a printing press having a longitudinal bed, a carriage reciprocable thereon, and an inking roller carried on said carriage, the improvements of an ink applicator roller journaled on said bed and arranged to be engaged by said rollers, an inking fountain for supplying a predetermined quantity of ink to said applicator roller, said inking fountain including a roll journaled on said bed, blade means for applying a layer of ink to the surface of said roll as said roll rotates, a ratchet secured to said roll, a rack unit reciprocably movable on said bed as a function of the cyclic movement of said carriage on said bed and engageable with said ratchet during a portion of its reciprocable movement to incrementally rotate said ratchet, a ductor roll movably mounted on said bed to engage either said fountain roll or said applicator roller, and means comprising a cam surface formed on said rack unit, said cam surface being constructed and arranged to engage said ductor roll with said fountain roll concurrently with the incremental rotation of said fountain roll, whereby said ductor roll is alternately moved into engagement with said fountain roll and said applicator roller during each cycle of movement of said carriage.

8. In a printing press having a bed, a carriage reciprocably movable on said bed, an inking roller journaled on said carriage and means for applying ink to said inking roller at one position of said carriage, the improvements of a driving chain positioned along said bed, power means for moving said chain, a sprocket journaled on said carriage and engageable with said chain, and means comprising an adjustable circumference pulley and belt connecting said sprocket and said inking roller in driving relation, and means for energizing said power means when said carriage is located at said one position, whereby said inking roller is driven by said chain in said inking position and rolls on said chain as a rack when said carriage traverses said bed.

9. In a printing press having a bed, a carriage reciprocably movable on said bed, an inking roller journaled on said carriage and means for applying ink to said inking roller at one position of said carriage, the improvements of a driving chain positioned along said bed, power means for moving said chain, a sprocket journaled on said carriage and engageable with said chain, means connecting said sprocket and said inking roller in driving relation, said last mentioned means comprising an adjustable circumference pulley and belt for driving said pulley, whereby adjustment of said pulley provides a surface speed of said form roller equal to the carriage speed relative to said form, and means for energizing said power means when said carriage is located at said one position, whereby said inking roller is driven by said chain in said inking position and rolls on said chain as a rack when said carriage traverses said bed, and braking means for said power means, and means for actuating said braking means concurrently with the deenergization of said power means to lock said chain to said bed to function as a rack.

10. In a printing press, a longitudinal, horizontal bed adapted to support a form, a carriage reciprocably movable along said bed, a post supported for vertical movement in said carriage, a bearing carried by said post, an inking roller having a shaft portion journaled in said bearing, a cam track disposed on an outside vertical wall of said bed, a cam follower supported for horizontal movement on said carriage and engageable with said cam track, a rack on said post, a rack connected to said follower, and a gear member rotatably mounted on said carriage and having toothed portions meshing with said racks so that movement of said cam follower horizontally will move said post vertically.

11. In the printing press defined by claim 10, manually operable means for supporting said post in a raised inoperative position.

12. In a printing press having a longitudinal bed, a carriage reciprocable thereon, an inking roller on said carriage and an applicator roll engageable with said inking roller, a fountain roll rotatably mounted on said bed for applying ink to said applicator roll, blade means for applying ink to said fountain roll as said roll rotates, a ratchet secured to said fountain roll, a bar movable longitudinally and reciprocably on said bed in timed relation to the movement of said carriage, a rack pivotally mounted on said bar and engageable with said ratchet, a follower affixed to said rack, an inclined cam on said bed engageable with said follower to move said rack into and out of engagement with said ratchet when said bar reciprocates, and means for adjusting the longitudinal position of said inclined

cam on said bed to determine the extent of engagement of said rack with said ratchet and the extent of rotation of said fountain roll during each reciprocation of said bar.

13. In a printing press having a longitudinal bed, a carriage reciprocable thereon, an inking roller on said carriage and an applicator roll on said bed engageable with said inking roller, a fountain roll rotatably supported on said bed, blade means for applying ink to said fountain roll, a bar movable longitudinally and reciprocably on said bed in timed relation to the movements of said carriage, a transfer roll resiliently urged into engagement with said fountain roll and movable into engagement with said applicator roll, a follower connected to said transfer roll, and a cam member on said bar engageable with said follower for moving said transfer roll into engagement with said applicator roll after ink has been applied to said transfer roll.

14. In a printing press as defined by claim 13, a ratchet secured to said fountain roll and a rack on said bar engageable with said ratchet

for rotating the fountain roll a predetermined amount during reciprocation of said bar.
